UNITED STATES PATENT OFFICE.

WILLIAM L. CLOUSE, OF TIFFIN, OHIO, AND ERNEST S. JEFFERIES, OF HAMILTON, ONTARIO, CANADA, ASSIGNORS TO THE NATIONAL MACHINERY CO., OF TIFFIN, OHIO.

FEEDER.

Application filed June 30, 1926. Serial No. 119,519.

This invention relates to the art of feeding wire stock to forming machines such as used in heading bolts and rivets, and in forming nuts, nails and springs, and other 5 articles, commonly produced from wire stock.

The material used in machines of the type referred to is supplied in coils and is fed continuously to the machine either direct 10 from the coil or into a furnace and thence to the machine. The operation of feeding mechanisms is generally satisfactory as long as an unbroken supply of stock can be furnished but when one coil of the stock has 15 been used and it becomes necessary to start a second coil to the machine, undesirable delays have been experienced which are costly and troublesome. Under the present practice clamps or other devices are used for 20 connecting the rear end of the used coil to the front end of the next succeeding coil but as the material is being fed continuously from the coil into the furnace and thence to the forming machine there is practically 25 no way in which the two coils can be satisfactorily connected without bringing the feeding mechanism to a complete stop.

It is an object of the present invention to overcome the disadvantages heretofore present 30 in the feeding of stock to machines of the class mentioned by providing a means whereby the rear end of a coil being fed to a furnace or directly to a forming machine can be held stationary without retarding the 35 feeding operation and for a sufficiently long time to enable the front end of another coil to be attached to the said held rear end either by clamps or by a welding method. Consequently the operation of the mechanism 40 is not retarded in any way and can be carried on continuously without undesirable delays.

With the foregoing and other objects in view which will appear as the description 45 proceeds, the invention resides in the combination and arrangement of parts and in the details of construction hereinafter described and claimed, it being understood that changes in the precise embodiment of 50 the invention herein disclosed may be made

within the scope of what is claimed without departing from the spirit of the invention.

In the accompanying drawing,

Figure 1 is a side elevation, more or less in diagram, showing the feeding mechanism, 55 a coiled wire being shown in position thereon.

Figure 2 is a section on line 2—2, Figure 1.

Figure 3 is an end section on line 3—3, 60 Figure 1.

Referring to the figures by characters of reference 1 designates a reel mounted for rotation and on which a coiled supply of wire, indicated generally at W, is adapted to 65 be placed. Mounted adjacent this drum is a feed drum 2 also mounted for rotation and provided, at one end, with a circumferential feed groove 3 and, at desired intervals, with additional grooves 4. Cooperating with the groove 3 is a feeding roll 5 formed with a peripheral groove 6 and this roll 5, which is mounted on a shaft 7, is adapted to be driven at any desired speed by any suitable mechanism, such as a belt, not shown, engaging a 70 pulley 8.

Grouped around the feed roll 5 are bending rolls 9, 10 and 11 and the rolls 5 and 10 are preferably so mounted on a pivoted structure 12 or the like that they can be 75 so moved bodily toward or from the drum 2.

Located adjacent the other end of the feeding drum 2 is a feeding roll 13 having a peripheral groove 14, this roll being suitably supported and adapted to be rotated by any 80 suitable means. Another feed roll 15 formed with a peripheral groove 16 is carried by a shaft 17 driven by any suitable means and is adapted to cooperate with roll 13.

The apparatus constituting this invention is adapted to be placed between the reel 1 carrying the coiled wire W and inlet f of the furnace F through which the wire is passed prior to its delivery to the forming machine. 95 The free end portion of the coiled wire is passed into the grooves 3 and 6 so as to be gripped by the walls thereof. Drum 2 is then rotated simultaneously with the roll 13 either by frictional contact between the roll 100

and drum or by any other suitable means. Thus the end portion of the wire will become coiled about the drum 2 and will be formed into large coils by the bending rolls 9, 10 and 11.

The wire is also extended between the rolls 13 and 15 and passes therefrom into and through the furnace (not shown) and thence to the header or other machine. The operation of the machine will cause the wire to be pulled longitudinally through the furnace and off of the rotating drum 2. The mechanism is so constructed that the wire will be fed to drum 2 slightly faster than it is withdrawn therefrom. Obviously, therefore, the coils supported by the drum 2 will slowly increase in size with the result that, as the end of the wire approaches drum 2 it becomes possible to stop the supply of wire to said drum without stopping the feeding of wire through the furnace to the forming machine. This is due to the fact that rolls 5 and 16 can be shifted away from the drum 2 and the continued feeding of the wire while the supply of wire to the drum is discontinued will result in the taking up of slack in the coils on the drum 2 and during this period of operation another coil of wire can be placed on the reel 1 and the forward end thereof connected to the rear end of the used coil by means of clamps or by welding. This operation can be completed before all of the slack on drum 2 has been taken up and without stopping the drum. The rolls 5 and 10 can then be returned into engagement with the wire and drum 2 and the new supply of wire will be fed to the drum 2 and to the furnace or the forming machine in the manner heretofore explained. Thus it will be seen that the feeding operation can be carried on continuously and all delays due to temporary stopping will be eliminated.

It will be understood of course that the rolls 13 and 15 can operate to take off the stock at any speed independently of the operation of the drum 2 and in some instances can be entirely displaced by the forming machine.

As before stated this mechanism is designed primarily for use in feeding stock from a coil through a furnace and thence to a forming machine but it will be apparent that the same mechanism can also be employed in connection with cold headers or other machines where no furnace is used. Among these may be mentioned cold nut machines, spring making machinery, wire nail machines, and any other type of machines to which stock is fed from a coil. In every instance the feeding mechanism of the machinery to which this invention is applied constitutes a means for pulling the material from the feeding mechanism herein disclosed but where a furnace is used for heating the material the rolls 13 and 15 also

constitute a means for pulling the material up to the time when said material is brought to position where it can be engaged by the feeding mechanism of the forming machine or the like. Therefore the term "pulling mechanism" or the equivalent thereof used in the claims can apply either to the rolls 13 and 15 or to the ordinary feeding mechanism of a header or the like.

What is claimed is:

1. Feeding mechanism of the class described including a drum mounted for rotation, having a peripheral groove, a rotatable annularly grooved roll cooperating with the grooved drum for gripping and guiding material directed therebetween, material pulling mechanism, and means for operating the same to withdraw material from the drum at a lesser speed than it is supplied thereto.

2. Feeding mechanism of the class described including a drum, a roll rotatable therewith, a second roll, said rolls cooperating to grip material and coil it about the drum, means for supporting said rolls for movement into or out of operative relation with the drum, thereby to feed or discontinue feeding material, respectively, and relatively movable rolls for engaging material and withdrawing it from the drum at a lesser speed than it is supplied thereto.

3. The combination with a structure for use in forming material, of mechanism for directing into said structure a continuously movable, unbroken supply of material, said mechanism including a support for coiled material, pulling mechanism for said material, feeding means for actuating the pulling mechanism, and means engaging the material for directing it into the pulling mechanism faster than it is fed by the pulling mechanism to the structure, thereby to build up a surplus of material between the pulling mechanism and the feeding means whereby one end of the material can be held and connected to one end of another length of material during the continuance of the feeding operation.

4. The combination with a structure for use in forming material, of mechanism for directing into said structure a continuously movable, unbroken supply of material, said mechanism including a reel for holding coiled material, a pulling mechanism for feeding the material continuously to said structure, and feeding means interposed between the reel and the pulling mechanism for building up and supporting a surplus of material between the pulley mechanism and the reel whereby one end of the material can be held and connected to one end of another length of material during the continuance of the feeding operation.

5. The combination with a structure for use in forming material, of means for simultaneously feeding material to said structure

and building up a surplus of material whereby one end of the material can be held and welded to one end of another length of material during the continuance of the feeding operation, said means including a reel for supporting a supply of coiled material for rotation, a pulling mechanism for engaging the material to feed it continuously to the structure and means for directing material from the reel toward the pulling mechanism at a greater speed than the speed at which the material is fed to the structure by the pulling mechanism, thereby to build up coils of surplus material between the reel and the pulling mechanism.

In testimony that we claim the foregoing as our own, we have hereto affixed our signatures.

WILLIAM L. CLOUSE.
ERNEST S. JEFFERIES.
